UNITED STATES PATENT OFFICE.

JOSEPH B. ULLMAN, OF WASHINGTON, DISTRICT OF COLUMBIA.

DESIGN FOR A RING.

61,354.

Specification for Design.

Patented Aug. 8, 1922.

Application filed June 6, 1922. Serial No. 2,551. Term of patent 7 years.

To all whom it may concern:

Be it known that I, JOSEPH B. ULLMAN, a citizen of the United States, residing at Washington, in the District of Columbia, have invented a new, original, and ornamental Design for a Ring, of which the following is a specification, reference being had to the accompanying drawing, forming a part thereof.

The words "Until death do us part," entwined with the flower design disclosed in the drawing, constitute a part and parcel of this new and ornamental design.

I claim:

The ornamental design for a ring, as shown.

JOSEPH B. ULLMAN.
